Application March 26, 1942, Serial No. 436,287

19 Claims. (Cl. 225—21)

1

This application is a continuation in part of my co-pending application S. N. 350,816, filed August 3, 1940, which became abandoned.

This invention relates to liquid dispensing and has as its principal object the provision of improvements in a method and apparatus adapted to dispense a carbonated beverage, particularly one of the pre-mixed variety in which the flavoring syrup and carbonated water are stored in mixed condition in supply drums and maintained under pressure and refrigeration to be dispensed in measured quantities, one cupful at a time, preferably in a coin-controlled dispensing machine.

Detailed objects of the invention are to overcome certain problems in connection with dispensing pre-mixed beverages which are carbonated; to provide means for maintaining uniform temperature and pressure conditions for the beverage or other liquid regardless of the load or dispensing rate, and regardless of whether or not the reserve beverage or liquid supply is low; to provide improved pre-cooling means in which the beverage is retained in quantity in a pre-cooling tank and is also passed through a pre-cooling coil in a refrigerating bath, and then retained in a measuring chamber cooled by the same refrigerating bath; to provide pressure-control means including pressure-regulating valve means and a novel relief venting means for causing a predetermined or artificial pressure drop which will always effect positive operation of the regulating valve means notwithstanding that quantities of beverage may be withdrawn in too small amount to cause otherwise normal operation of the regulating valve means; to provide a coordinated valve system and pressure-regulating means co-acting to effect delivery of a foam-free beverage of predetermined or requisite volume and gas content, which will remain uniform regardless of the operating load upon the machine, so that a palatable beverage will always be dispensed by the machine.

Other objects, advantages and aspects of novelty of the invention reside in the method of dispensing the beverage as well as in details of construction and operation of the apparatus described hereinafter as a preferred embodiment of means for carrying out the method and achieving the aforesaid objects, all of which will appear from the following description taken in view of the annexed drawing in which:

Figure 1 is a front diagrammatic view of a drink vender embodying the novel drink vending apparatus;

Figure 2 is a sectional view taken along the line 2—2 of the vender shown in Figure 1, and shows

2

the arrangement of the containers and the drink vending apparatus therein;

Figure 3 is an enlarged sectional view of the constant pressure container, and its "snifter" or auxiliary vent valve;

Figure 4 is a sectional view of the "snifter" valve shown in its open position;

Figure 5 is a side view partly in section of the improved vending apparatus with a typical wiring 10 diagram for operating the same;

Figure 6 is a sectional view through a modified arrangement of the machine with parts shown in elevation, and a schematic control circuit.

Referring to Figures 1 and 2 of the drawings, 15 the drink vender is housed in a refrigerated cabinet 10 within which is provided a wet refrigerated brine tank 11. The refrigerated cabinet 10 is, in this case, maintained at a temperature of about 45° and the brine tank 11 is kept at a temperature 20 between 31° and 36° (Fahrenheit).

Within the refrigerated cabinet 10, and on the floor thereof rests a bulk mixed drink container 12 to which is connected, by a conduit 13, a drum 14 of carbon dioxide gas. Adjacent the container 12 and on the floor of the refrigerated cabinet 25 rests another container 15 which is connected to the container 12 by a conduit 16. The pressure from the drum 14 of CO₂ gas is regulated by a valve 17 provided thereon. The container 12 has inlet and outlet valves 18 and 19, respectively.

Within the brine tank 11 is positioned part of the novel pressure-regulating means in the form of an automatic snifter or carbonated drink container 21 and a measuring and defoaming device 22.

The drink container 21 comprises a cup-shaped member 21a which has an open top on which fits a cover 23. An annular shaped member 24 encircles the member 21a and rests against a bead 25 provided around the periphery of the cup-shaped member 21a. A suitable gasket 26 is provided between the cover 23 and the edge of the open top of the member 21a. Bolts 27 secure the cover 23 to the annular member 24. A conduit 28 connects the container 15 and the carbonated drink container 21.

In the conduit 28 is provided a pressure-regulator valve 29 which comprises a body portion 31 in which is threaded a part 32, between which portion and part 32 is held a resilient rubber diaphragm 33. In the part 32 is threaded a nut 34 in which is seated a spring 35 that rests against a circular disc 36 which contacts the diaphragm 33. In the body portion 31 is threaded a nut 37 in which is 55 movably mounted a conical valve 38 that is

adapted to seat itself in a conical opening 39 in the body portion 31. A spring 41 is inserted between the valve 38 and the nut 37. Pressure is applied to the containers 12 and 15 by the tank of CO₂ gas 14 through the conduits 13 and 16. From the container 15 pressure is applied through the conduit 28 into the pressure regulator 29 which regulates the pressure applied into the drink container 21, by permitting valve 38 to open when the pressure in the container drops below a certain value. The construction and operation of such valves is known.

From the foregoing description it should be noted that a considerable number of cold drinks are always in the machine. The container 15 holds a number of drinks which are maintained at a temperature of about 45°, and the container 21, which is in the brine tank 11, holds a number of drinks at a temperature of between 31° and 36°. These temperatures may be varied, but they are given here merely to illustrate the advantages of my machine. For example, when the container 12 is empty, a considerable number of cold drinks are still in the machine, therefore, the warm drink from a newly installed bulk container 12 has time to become cooled before drinks are tapped therefrom. By this arrangement, a small economical refrigeration unit may be used in the machine, with adequate reserve refrigeration for relatively heavy demands for beverage.

The pressure regulator 29 is adjusted by turning the nuts 34 and 37 so as to cause this valve to close when the pressure in the snifter tank 21 reaches a desired level. I have found that it is desirable to maintain not less than twenty-three pounds' pressure within the container 21 so as to maintain at least four volumes of gas in the drinks to be dispensed therefrom. A gauge 41 is provided on the cover 23 so that the pressure within the container may be readily noted.

Within the container 21 a float controlled valve 42 is provided. The cover 23 has an opening in which is fitted a part 43 which has a very narrow axial bore providing a small escape orifice 43x. The part 43 extends downwardly through the opening in the cover 23, and a bracket 44 is secured at the inside thereof by a nut 45 which is turned onto a threaded portion of the part 43. The valve 42 comprises a bulb or float 46 from which extends a tube 47 which is movably mounted in alined openings provided in the bracket 44. A rubber 48 inserted in the end of the tube 47 is held therein by a cotter pin 49. As shown in Figure 3, the rubber 48 moves upwardly into engagement with bore within the part 43 due to the buoyancy of the bulb 46 in the liquid within the container 21. A conduit 51 is connected in the part 43 by a nut 52 and to an electromagnetic valve 53.

A conduit 54 is secured in the cover 23 and extends downwardly toward the bottom of the container 21 so as to take the liquid from the bottom thereof. A fitting 55 provided on the cover 23 connects the conduit 54 with a conduit 56 which is connected to an electromagnetic valve 57, and thence into the measuring and defoaming device 22.

The measuring device 22 comprises a closed container 58 which is provided with inlet and outlet passages 59 and 61 respectively. A conduit 62 connects the electromagnetic inlet valve 57 and the inlet passage 59 of the container 58. A conduit 63 connects the outlet passage 61 and an electromagnetic outlet or dispensing valve 64 from which extends a pouring spout 65.

At the top of the closed container 58 extends a flange 66 on which rests an enclosed bulb 67. A cover 68 is threaded onto the top of the container 58 between which is disposed a gasket 59 so as to seal the cover 68 to the container.

The cover 68 is provided with a threaded opening 69 in which is secured a tubular part 91 having an axial bore 72 and a transverse opening 73. At the end of the tubular part 71 is secured a solenoid 74 from which extends a movable rod 75 at the end of which is provided a circular part 76. A compressible part or rubber washer 77 encircles the rod 75 so as to form a valve seat between the circular part 76 on the rod 75 and the end of the tubular part 71. Upon deenergizing the solenoid 74, the rod 75 moves downwardly and opens the valve. This valve is a main vent valve, the purpose of which will appear shortly.

The electromagnetic valves 53, 57, 64, and the solenoid 74 are operated by a timing device 78 which is of the type disclosed in the Nicolaus Patent No. 2,138,243 of November 29, 1938. A functionally comparable timing device is shown in Fig. 6 herein, and will be described later. However, any suitable type of timing device may be used to operate the valves 53, 57, 64, and the solenoid 74, and therefore, it is believed that it will be sufficient to say that the timer 78 is adapted to be connected to a source of electrical energy by the plug 79, from which extends a main wire 81 and a return wire 82. The wire 82 extends into the timer 78 and is connected to a series of switches provided therein. The main wire 81 is provided with a switch 83 from which the wire 81 extends into each of the electromagnetic valves 53, 57, 64, and the solenoid 74.

The timing device 78 is so constructed that when the switch 83 is operated, either manually or by a coin operated mechanism, for example, the machine operates only during the cycle of operation of the timer 78. Upon operation of the timer 78, the solenoid valve 74 is opened to vent head gas from the measuring chamber and under certain conditions to be explained, the auxiliary vent valve 53 may open at the same time as the main vent valve 74. Next, the electromagnetic dispensing valve 64 is closed. Finally, the electromagnetic inlet valve 57 is opened and the cycle is complete. When the timer has completed its cycle of operation, the valves 53, 57, 64, and the solenoid vent valve 74 are all closed.

The operation of the form of machine shown in Figures 1 to 5 will now be explained. The bulk container 12 is readily connected to the system through the valves 18 and 19. The container 15 preferably stays in the refrigerated cabinet 10 and the drinks therein are always maintained at the temperature within the cabinet.

Pressure is applied into the container 12 through the conduit 13 from the tank 14 of CO₂ gas. From the container 12 the drink is directed into the container 15 through the conduit 16, and from the container 15 through the conduit 28 into the drink container 21. The pressure of the drink from the conduit 28 to the drink container 21, however, is controlled by the pressure regulator valve 29 so as to maintain any desired given constant pressure within the drink container 21 within certain limits determined by the sensitivity of the valve. By maintaining a given constant pressure within the container 21, the desired volume of gas or charge in the drink may be maintained therein, and, more important still, the requisite volume of beverage will positively be forced into the measuring chamber 22, and proper

defoaming action, which depends upon the existence of a certain pressure behind the measured drink, as explained in my co-pending application S. N. 248,114, now Patent No. 2,284,880, dated June 2, 1942, can therefore be reliably effected in the chamber 22. The drink is then directed through the conduit 56 to pass into the measuring device 22 while valve 57 remains open.

The auxiliary vent valve 53 is energized to be held open while the main vent valve 74 is open, but the rate of gas escape through the constricted orifice 43x (when open) is comparatively slight to the sudden and total pressure relief effected through the main vent valve 74.

When a certain number of drinks, usually about seven are removed from the container 21, the float valve 42 moves downwardly and permits the head pressure in the container to escape through the small orifice 43x in conduit 51 when valve 53 is opened during a dispensing operation. By releasing pressure in the container 21, a positive, artificial, pressure drop is caused therein calculated to effect certain opening of the regulating valve, so that there will at once be a replenishment of beverage in container 21, as well as an increase in pressure, sufficient to drive the beverage into the measuring chamber in full measure and with adequate pressure to dispel the foam which inevitably arises therein.

It will be observed from Fig. 3 that the liquid level may rise considerably after float valve 48 is closed. It is for this reason that the latter valve usually doesn't open until several drinks have been withdrawn, and the explanation for this fact is that if there is a sufficient pressure and volume of beverage in the container 21 to force the level above the opening point of the float valve, then it is unnecessary to snift off any gas. However, if pressure tends to be low on the supply side of the line, the regulating valve 29 may not open because of its limited sensitivity, then the pressure must be maintained at least at the level necessary to close the float valve 48, otherwise positive measuring and defoaming cannot be automatically assured in chamber 22. It is to be understood, however, that this dispensing method and the apparatus for carrying it out, as just described, operates equally well if the float valve means 42-45-46-48 be omitted; the said valve means is desirably employed to effect economies in the gas supply, since it is ordinarily not necessary to artificially drop the pressure in container 21 to cause operation of the regulating valve 32 if the supply pressure is high enough to keep the level in tank 21 at a point where the said float valve would be closed if it were employed. Such a condition in tank 21 would exist only if the pressure were very high, so that it would not matter whether the regulating valve failed to operate while this condition persisted.

Frequently gas pockets form in the supply lines and barrels, as well as at the head of the pre-cooling and snifing or regulating container 21, and the automatic regulating means just described, obvious faulty operations due to these causes, as well. In addition, some defoaming is achieved in container 21, since bubbles and foam always ensue when a highly carbonated beverage of the class described is transferred through pipes, connections, and varying pressure levels.

In Fig. 6 there is shown a modified form of the apparatus, in which the precooling, pressure-regulating or snifing container is removed from the refrigerating bath, but is nevertheless kept

cool by the latter, as will appear; and there is additionally provided a pre-cooling connection between the snifter tank and measuring chamber, which connection is adequate to hold several drinks, and is immersed in the refrigerating bath.

As in the case of the structure of Figs. 1 and 2, the apparatus of Fig. 6 is housed in an insulated cabinet 110, in which there are disposed two bulk supply drums 111 and 112, analogous to containers 12 and 15 of Fig. 1. The two supply drums are coupled by a pipe 113 which leads via its end 113a from the lower region of drum 112 into the upper region of drum 111 at 113b.

Drum 112 is connected by conduit 114 to a drum 115 of carbon dioxide gas confined at a pressure considerably above that which would ordinarily be necessary to drive the total supply of beverage through the dispensing circuit. In other words, the gas supply is calculated always to be in excess, as to quantity and pressure, of the maximum needs for each loading of the machine. This gas pressure causes the beverage in drum 112 to be transferred via pipe 113 into drum 111 as the latter becomes emptied of its contents, beverage from drum 111 passing from the intake portion 116 at the bottom thereof through pipe 116a and thence through a pressure-regulating valve 117 (similar to valve 29 of Fig. 5), and via conduit 118 into the upper region of a reserve pre-cooling drum or receiver 119, situated in the upper or cooling compartment, which is separated from the lower compartment by partition 9.

From the pre-cooling drum, the beverage passes via conduit 120 through a pre-cooling coil 121 and thence through an inlet valve 122 into a measuring chamber 123 disposed, with the coil 121, in a brine bath, or other cooling medium 124 arranged to be cooled by any suitable refrigerating means (not shown, since many types are available) and which includes refrigerating coils 138, which means also serves to cool the reserve drum 119 through the medium of the bath 124 since the latter also cools the compartment in which the drum 119 is situated.

At the lower end of the measuring chamber 123 there is a discharge pipe 125 which passes through an electro-magnetic dispensing valve 126 and terminates as a delivery spigot 127 above a cup 128 (positioned therebelow by automatic cup dispensing means schematically indicated at 150).

Additional features of importance are the provision of an electro-magnetic vent valve 128 connected by pipe 129 with the top of the measuring chamber 123; and an auxiliary electromagnetic vent valve 130 connecting into the top of the pre-cooling drum 119 through a pipe 131 having a small orifice of the order of about $\frac{3}{64}$ inch in diameter (similar to orifice 43x in Fig. 3).

The small orifice leading into pipe 131 is normally open, but may be closed by a valve member 132 disposed at the upper end of guide rod 133 on a float 134, which is mounted to rise and fall in a bracket 135 secured to the underside of the coupling head 136 which connects the various pipes with the pre-cooling drum or receiver 119 at the top thereof.

The operation of this embodiment is also automatic and preferably coin-controlled, although no coin control means is shown herein since the invention per se is not concerned therewith. As a part of the control means there is shown schematically in the drawing a timing device like the unit 78 of Fig. 5, including a timing motor 140

which would ordinarily be set into operation by the patron, as by a coin controlled starting switch (not shown), and which is arranged to complete a cycle of rotation of certain control means such as the cams A, B, C, and D, each of which controls the opening and closing of a corresponding switch 141, 142, 143 or 144. Each of the foregoing switches has one of its terminals connected to a common conductor or ground G, to which common ground is connected also one terminal of a power source indicated as battery 145. The remaining terminal of this battery or power source is connected via conductor 146 to vent valve 130, the inlet valve 122 and via conductor 147 to one terminal of the dispensing valve 126.

The valve switches 141, 142, 143, and 144 are normally open. Upon deposit of the starting coin in the machine, or energization of the motor 140 from any other source of control, the cam shaft 140a rotates slowly and the switches remain open so long as the offset nose portions 141a, 142a, 143a, and 144a ride on the peripheral portion of their respective cams A, B, C, and D. The first thing that happens in each cycle of operation of the cam shaft, is the closing of switch 141 by action of the nose portion 141a dropping into the slot A¹. This results in energization of certain cup dispensing mechanism, schematically indicated by the dotted line representation 150, such energization being effected via a conductor 151, so that the dispenser may be energized from a connection 160 to battery 145, resulting in the deposit of cups 128 in position beneath spigot 127.

Meanwhile switch 142 is closed by action of the nose portion 142a thereof dropping into the peripheral cam slot B', with the result that the inlet valve 122 is energized, the circuit for this operation being completed from the ground G to switch 142, through the closed contacts of the latter, and via conductor 152 through the electromagnetic operating coil of valve 122 and thence via conductor 146 to battery 145.

The inlet valve 122 remains open long enough for a quantity of cool beverage from coils 121 to enter the measuring chamber 123, such action of the beverage resulting in the creation of a considerable amount of foam owing to the relatively low pressure in the measuring chamber at the time the beverage enters under considerably higher pressure from the supply line. This foaming of the beverage releases a certain amount of gas which compresses the air in the head space at the top of the measuring chamber with the result that a limited amount of beverage will be admitted to the chamber, and this limited amount is calculated to the desired measure of beverage to be dispensed by controlling the temperature and the pressure in the supply line.

Since these pressures and temperatures must be more or less empirically determined for the various operating conditions to be encountered, only one set of suitable values will be given by way of example. Satisfactory results are obtained by maintaining a gas pressure from 25 to 30 lbs. per square inch on the supply side of the line, while the temperature of the beverage in the cooling coils and particularly in the measuring chamber, is preferably maintained between 31° and 36° F. Similar temperatures may obtain in the pre-cooling drum 119 if the dispensing rate is slow by reason of the fact that the drum is situated in the same compartment with the cooling bath 124 and subject to refrigeration from the same source.

Back pressure in the measuring chamber 123

limits the amount of beverage which can enter the latter, and as the back pressure begins to operate, the foam is collapsed and restored to liquid form with amounts of head gas in the chamber also restored to the liquid. The exact amount of liquid to be dispensed is thereby automatically measured off by action of back pressure in the measuring chamber, whereupon the beverage is prepared for transfer to the cup by relieving the excess head gas in chamber 123 as a result of closing switch 143 by rotation of cam C to present the slotted peripheral portion C' beneath the offset 143a of the switch permitting the latter to close. Closure of switch 143 effects simultaneous energization of both the main vent valve 122 and the auxiliary vent valve 130 by a circuit which includes one side of the operating coil vent valve 130, juncture 148 connecting with one terminal of the operation coil for vent valve 122, and switch 143 connecting ground G via conductors 153 and 154 to the remaining terminals of each of the operating coils of valves 128 and 130.

Opening of vent valve 122 permits the head gas to be popped-off quickly from above the surface of the liquid beverage in chamber 123, this being a very important step in the dispensing cycle if the drink is to be delivered without objectionable foam and loss of gas.

It will be recalled that the auxiliary vent pipe 131 was stated to be provided with a very small orifice, which results in a relatively slow escape of gas, while the auxiliary valve 130 remains open, to the pre-cooling drum 119, for purposes of restoring a desired pressure condition as will be described hereinafter. This orifice arrangement is the same in both embodiments, and is illustrated in Fig. 4, attention being called to the orifice as indicated at 43x.

Shortly after the opening of the main vent valve 122, switch 144 is closed by rotation of cam D in the manner heretofore described in connection with the operation of the other switches, with the result that circuit is completed from ground G via conductor 155 to the coil of the dispensing valve 126 so that the latter is open while the main vent valve 122 remains open, cams D and C being designed with this object in view—that is to say, to maintain switches 143 and 144 closed until the measured quantity of beverage has had time to be delivered by gravity from the measuring chamber 123 through the dispensing spout 127 and into cup 128.

If the main vent valve 122 is not held open while the drink gravitates into the cup, escape of gas and residual head pressure in the measuring chamber would cause the creation of objectionable amounts of foam in the drink dispensed.

By the time the measured quantity of beverage has descended into the cup, the operation cycle for the control cams has been completed and motor 140 is automatically deenergized, whereupon the customer may remove the cup 128 from the machine by raising glass door 156 at the front of the machine.

The usual volume of beverage to be dispensed upon each cycle ranges between ten and twelve ounces, but this volume is too small to cause a sufficient change in pressure in the drum 119 to effect positive operation of the regulating valve 117, and in fact the withdrawal of several measured quantities or cups of beverage will not effect such operation uniformly, yet the withdrawal of a number of drinks would obviously effect the gas pressure existing in the drum 119, and since,

as heretofore discussed, pressure at the supply side is important not only to collapse foam in the measuring chamber, but also to predetermine the amount of beverage to be dispensed, it becomes necessary to constantly rectify the pressure on the supply side, and this is accomplished by the operation of the auxiliary vent valve which, although the amount of gas relieved thereby is relatively small, permits enough gas to escape to create an artificial pressure drop sufficient to positively effect operation of the regulating valve 117, with the result that additional quantities of beverage and gas are immediately restored to the drum 119. This effects prompt replacement of additional quantities of beverage which may become cooled prior to reaching the cooling coil 121, and also increases the volumetric displacement in the drum with consequent rise in internal pressure apart from any additional volumes of gas which may have been entrained by the replacement liquid.

As described in conjunction with the operation of float valve 48 in Fig. 5, as soon as the liquid level is raised in drum 119 of Fig. 6 to a point where the pressure condition therein is suitable (i. e. capable of forcing the desired volume to be measured into chamber 123), the float 134 is likewise raised sufficiently to cause valve 132 to close the orifice leading into pipe 131 and through the vent valve 130. However, the arrangement is such that the restored liquid level rises beyond the point where the float valve first closes, with the result that it requires the withdrawal of as many as ten to twelve drinks from drum 119 before the float valve will again open to render the auxiliary vent valve 130 effective. When a volume of liquid is withdrawn equivalent to ten or twelve drinks as aforesaid, the pressure condition in the drum 119 is such that further withdrawal might endanger the uniformity of the volume and gas content of subsequently removed quantities should the regulating valve fail to open, and it is therefore at this juncture that the float valve renders the auxiliary vent valve effective to restore the desired pressure and volume condition in drum 119. However, float valve means 132—134 may be omitted for reasons heretofore set forth in the description of float valve means 42—48.

The liquid measuring and defoaming functions performed by the measuring chamber are covered in my aforesaid co-pending application S. N. 248,114, but in the present application there are the new features of pressure control or rectification and immersing the measuring chamber in a cooling bath along with pre-cooling coils 121, one purpose of which will now be described.

In a preferred mode of operation, the inlet valve 122 is opened immediately following the closure of the dispensing and main vent valve in order to admit a quantity of beverage into the measuring chamber to be held there pending withdrawal upon the next operation of the machine, the purpose of this being to transfer a quantity from the pre-cooling coil 121 to make room for another quantity which may be cooled in the interval between subsequent withdrawals. The coils 121 are primarily a heat-exchange and storage means designed to hold about six 12 oz. drinks. In this way the capacity of the machine with respect to its maximum refrigerating load, is considerably enlarged, and this becomes of great importance where the machine is situated in a busy location and subject to frequent operation. The provision of the pre-cooling drum

119 in cooperation with the aforesaid cooling features provides additional capacity for the device, and it is possible by such an arrangement to build up a reserve of three-quarters ton of refrigeration with a refrigerating machine rated at one-quarter ton.

If the machine is being operated under a heavy load, it is possible that the entire contents of the reserve pre-cooling drums may be withdrawn. The capacity of these drums is about 7½ gallons, equivalent to approximately 100 drinks, and in an extreme condition it may be that one or more of the supply drums 12, 15 or 11, 12 has been installed at an elevated temperature of perhaps 80 degrees. Even under these extreme conditions the arrangement of the pre-cooling coil 121 (or chamber 21) in the same refrigerating medium with the measuring chamber makes it possible to cool the beverage down to an acceptable temperature by the time it is ready for dispensation.

In designating the drum 119 as a "pre-cooling" means, there is no intention to employ a limiting term, but rather a convenient designation suggestive of one of the functions of the drum. Obviously, the drum 119 is of considerable importance in its pressure regulating functions, as well, even though it is not immersed in the bath as is the container 21 of Fig. 2. If the liquid level is normal in the drum or vessel 119, the float valve means 132—134 will prevent escape of gas through the auxiliary vent valve 130. If the liquid level is low however and the float 134 descends so as to open the restricted passage to the auxiliary vent valve, then gas will be relieved directly from the drum 119 during the approximate fifteen-second interval while the vent valves remain open, while the excess head gas in the measuring chamber 123 will be relieved by the main vent valve 122.

Following the operation of the vent valves as aforesaid, switch 144 will be operated to energize the dispensing valve 126 which will be held open while the main vent valve 122 remains open so as to permit the measured quantity of beverage to drain by gravity from the chamber 123 into the cup 128.

Relief of gas from the pre-cooling receiver 119 is calculated always to effect an operation of the regulating valve 117 so that there will be an influx of beverage from the supply drum 112 to drum 119 to restore the necessary pressure therein and to increase the volume of liquid to be subjected to pre-cooling temperatures.

In addition to the pre-cooling feature of such transfer of beverage to the pre-cooling drum, the pressure condition in the latter is brought up to the required standard to assure that there will be no short measures and that there will be adequate gas content in the beverage, since measurement depends upon the gas pressure at a given temperature, and since it is absolutely necessary in order to deliver an acceptable beverage that there be at least a certain minimum gas content therein (for example about 4.0 to 5.0 volumes). The defoaming operation also depends upon the existence of a minimum pressure in the supply side of the system ahead of the measuring chamber. In general, the operation of the embodiments shown in Figs. 1 to 5, and in Fig. 6, is the same, the differences being largely structural and relating to the arrangement of a pre-cooling storage coil 121 in the cooling bath with the measuring chamber, instead of having the pressure-regulating or snifting chamber 21 immersed in the brine tank 11.

as in Fig. 2. The arrangement of Fig. 6 makes it possible to employ a smaller tank for bath 124, while enlarging the refrigerating capacity, since drum 119 is also appreciably cooled by virtue of being disposed in the same insulated compartment with the bath.

It is the intention that the foregoing disclosure shall not be limited to the precise arrangement shown and described, but shall be accorded liberal interpretation with the inclusion of reasonable equivalents and substitutions not inconsistent with the appended claims and the scope and nature of the improvement, and while the invention is especially suited to the vending of pre-mixed carbonated beverages, it is contemplated that it may be applied to control systems for other liquids, as well.

I claim as my invention:

1. Apparatus for dispensing a carbonated beverage comprising means providing a cooling medium, a measuring chamber cooled by said medium, a normally closed vessel, connection including normally closed inlet valve means between said vessel and chamber, means for supplying beverage under gas pressure to said vessel, automatic regulating valve means interposed between said supplying means and vessel to admit quantities of fluid to the latter when the pressure condition therein drops to a predetermined value, means for venting said vessel and chamber, and means for dispensing beverage from said chamber, and control mechanism for effecting operation of said venting means, said dispensing means, and said inlet valve means in the order named.

2. Dispensing apparatus comprising: a cooling medium, a measuring chamber in said medium, a beverage receiver, a beverage supply container, automatic regulating valve means between said container and receiver to admit beverage to the latter when the pressure therein reaches a predetermined condition, a source of gas pressure connected to displace beverage from said container to said receiver under control of said regulating valve means, a valved connection between said receiver and measuring chamber, dispensing valve means operable to permit passage of beverage from said chamber, venting valve means for said receiver and for said chamber, and control means for opening and closing said valved connection to admit beverage to said chamber, and subsequently opening the venting valve means for both the receiver and chamber, and then opening said dispensing valve means.

3. Dispensing apparatus including a beverage receiver, means for supplying beverage under gas pressure to said receiver, dispensing means for effecting discharge in succession of measured quantities of beverage from said receiver, regulating valve means interconnecting said supply means and receiver and operable upon a predetermined lowering of pressure in the receiver to admit beverage thereto, and means controlled cooperably with said dispensing means for venting said receiver to artificially lower the pressure in said receiver sufficiently to cause operation of said regulating valve means independently of the volumetric displacement of beverage in said receiver responsive to discharge of beverage therefrom.

4. Dispensing apparatus including a beverage container, means for supplying beverage under gas pressure to said container, said gas pressure being maintained in excess of a predetermined minimum value, means for dispensing beverage

from said container, a gas escape valve operatively associated with said container, means controlled by the volume of liquid in said container for rendering said escape valve ineffective when the liquid volume exceeds a predetermined amount in said container, automatically acting means for normally closing off communication between said container and supply means when the pressure in the container is above a predetermined minimum value and for opening such communication when said last-mentioned pressure is below said minimum value thereof, and means coacting with said dispensing means upon each dispensing operation thereof for opening said escape valve for the purpose of causing an artificial pressure drop in said container, provided said volume-controlled means does not render the escape valve ineffective as aforesaid, whereby to effect positive operation of said means for opening communication to the container from the supplying means as aforesaid.

5. Dispensing apparatus including a beverage receiver, a beverage supply container connected to said receiver through a regulating valve adapted to open at a predetermined pressure differential between said receiver and container, means for applying gas pressure behind the beverage in said container, a measuring chamber, a vent valve for said chamber, a dispensing valve for said chamber, an escape valve for said receiver, a float valve arranged to render said escape valve ineffective when greater than a predetermined volume of beverage is in said receiver, a pre-cooling connection between said receiver and measuring chamber and including a normally closed inlet valve, means for cooling said chamber and said pre-cooling connection, at least, and operating mechanism arranged to open said escape and vent valves, then open said dispensing valve while said vent valve remains open, and after closing said escape, vent and dispensing valves, to open and close said inlet valve long enough to permit a measured quantity of beverage to enter said measuring chamber in readiness for the next dispensing operation.

6. The combination, with means for storing a supply of beverage, and means for dispensing beverage from said storing means, of means for maintaining said beverage under a desired gas pressure, said means comprising a source of gas pressure connected to said storing means, regulating valve means interposed between said source of pressure and said storing means and operable to admit fluid under pressure from said source when the pressure in said storing means drops below a predetermined value, and auxiliary means, actuated automatically each time said dispensing means is operated, for causing a sufficient amount of gas to escape from said storing means to effect an artificial pressure drop therein to a value at least equivalent to said predetermined value whereby to effect positive operation of said regulating valve means.

7. The combination of claim 6 further characterized by the provision therein of means for automatically rendering said auxiliary means for producing an artificial pressure drop ineffective when the liquid volume is greater than a predetermined value in said storing means.

8. In a dispensing system, in combination, means for storing a supply of liquid, means for applying gas pressure to the stored quantity of liquid, means for dispensing the liquid, means providing a pre-storage compartment ahead of said dispensing means and connected with said

supply means to receive liquid from the latter, pressure regulating means interposed between said supply means and said pre-storage means and operable to admit liquid under pressure to said pre-storage means when the pressure condition in the latter reaches a predetermined state, and means including a venting device controlled cooperably with the said dispensing means and actuatable on each dispensing operation of said dispensing means for relieving gas from said pre-storage compartment upon a dispensing operation whereby to create said predetermined pressure state in the pre-storage compartment to effect positive operation of said regulating means together with control connections between said venting device means and said dispensing means for simultaneously actuating said means for the purposes set forth.

9. The combination of claim 8 further characterized by the addition thereto, of means controlled by the volumetric liquid displacement in said pre-storage compartment for preventing effective operation of said venting device to relieve gas from said pre-storage compartment, when the volumetric liquid displacement therein rises above a predetermined amount.

10. In a beverage dispenser, the combination, with pressure-controlled drink measuring means, of gas regulating means comprising a beverage receiver connected in advance of said measuring means, means for storing a supply of beverage, normally closed automatic regulating valve means connecting said storing means with said receiver, means for maintaining a head of gas behind the beverage in said storing means, an escape valve of restricted orifice for said receiver, means for opening said escape valve in correspondence with each measured quantity of beverage passed through said measuring chamber, said escape valve means being arranged to cause a pressure differential between said receiver and storing means to effect positive opening of said regulating valve means to cause an influx of beverage and gas into the receiver, and a float valve in said receiver normally closing off passage to said escape valve when the receiver is loaded, and operable by reduction of the beverage content therein below a predetermined level to open passage from the receiver to the escape valve.

11. In a carbonated drink vending apparatus comprising a bulk container in which there is a ready mixed carbonated drink, means supplying gas to the bulk container so as to place the drink therein under pressure, a second container having a displacement-responsive valve with which is operatively associated an electrically controlled vent valve, a pressure-regulating valve operatively associated with the second container for maintaining a minimum displacement pressure therein, means for directing the drink from the bulk container to the pressure-regulating valve, a second electrically controlled valve, means for directing the drink from the second container to the second electrically controlled valve, and electrical timer means for operating said electrically controlled valves, the displacement valve serving to alter the constant displacement within the second container to cause an operation of the regulating valve.

12. A carbonated drink vending apparatus comprising a bulk container in which there is a ready-mixed carbonated drink, a gas drum connected with the bulk container so as to place the drink therein under pressure, a second container having a float-operated valve to vent gas from the

second container, a pressure-regulating valve associated with the second container for maintaining a desired pressure therein, means for directing the drink from the bulk container to the pressure-regulating valve and into the second container, a measuring device, and means for directing the drink from the second container to the measuring device, auxiliary vent control means normally rendering said float valve ineffective to vent gas as aforesaid, and means for operating said auxiliary control means at least once for each measuring operation of said measuring device.

13. A drink-vending apparatus comprising a bulk container adapted to contain a ready-mixed drink, pressure supplying means connected with the bulk container so as to place the drink therein under pressure, a second container to receive said ready-mixed drink, a pressure regulating valve associated with the second container, means for directing the drink from the bulk container to the pressure regulating valve and into the second container, auxiliary valve means associated with the second container, a measuring device having an inlet and outlet, valve means associated with said inlet and outlet, a gas relief valve on said measuring device, means for directing the drink from the said second container to the inlet valve of the measuring device, means for opening the outlet valve and the relief valve on said measuring device so that the drink therein may drain therefrom by gravity, means for opening said inlet valve of said measuring device at a time when the relief and outlet valves are closed so that the measuring device may be re-filled, and means for opening the auxiliary valve means associated with the second container at a time following opening of said outlet valve so that the pressure therein may be reduced by an amount sufficient to cause operation of said regulating valve.

14. A drink-vending apparatus comprising a bulk container in which there is a ready-mixed drink, means connected with the bulk container for placing the drink therein under pressure, a second container having gas relief valve, means for directing the drink from the bulk container to the second container, pressure-responsive means for controlling passage of the drink to the second container as aforesaid, a measuring device having an inlet and an outlet, valve means associated with the inlet and the outlet, means for directing the drink from the second container to the inlet valve of the measuring device, means for operating the outlet valve and then the inlet valve, a vent valve for the measuring device and means for operating the latter, prior to opening of said outlet valve and means for operating the relief valve on the second container during the operation of the said vent valve.

15. A drink-vending apparatus comprising a bulk container in which there is a ready-mixed drink, means for placing the drink in the bulk container under pressure, a second container in which there is stored a ready-mixed drink, pressure-sensitive means for directing the drink from the bulk container into the second container and operable when the pressure therein drops below a certain value, means for directing the drink out of the second container, and valve means partly controlled by level of the drink in the second container and partly controlled coincidentally with the operation of said directing means for releasing the pressure in said second container

to at least said certain value, to cause positive operation of said pressure-sensitive means.

16. An automatic sniffer for a carbonated drink-vending apparatus adapted to operate through a given cycle, comprising: a carbonated drink container, means for supplying carbonated drink to said container automatically when the pressure in the container drops below a certain value, means for directing the drink out of the container under pressure, valve means associated with the container and operably controlled by movement of the drink into and out of the container, and a second normally closed gas escape valve means associated with the first valve means and adapted to be opened at a time during the cycle of vending operation of the vending apparatus.

17. In a beverage dispenser, means for controlling the fluid pressure characteristics of the beverage dispensed under pressure from a bulk container, said means comprising: in combination, a bulk beverage container, a beverage receiver connected to receive beverage from said container, means for applying pressure to the beverage in said container at a pressure greater than necessary to drive the beverage into said receiver, regulating means for admitting beverage from said container to said receiver responsive to a pressure drop of predetermined magnitude in said receiver, a measuring chamber, inlet valve means connecting said chamber with said receiver, dispensing valve means providing egress for beverage from said chamber, main pressure-relieving means for said chamber, auxiliary pressure-relieving means for said receiver, means for actuating said dispensing valve means, said main and auxiliary pressure-relieving means, and said inlet valve means in timed relation constituting a dispensing cycle in which said pressure-relieving means is actuated in advance of dispensing operation of said dispensing valve means, and said auxiliary relieving means effects pressure relief at a slower rate than said main relieving means but sufficient to create a pressure drop of at least said predetermined magnitude in said receiver in a time interval between successive operations of said inlet valve means.

18. The invention defined in claim 17 further characterized by the provision of means acting to render said auxiliary pressure-relieving means

ineffectual when the volume of liquid beverage in said receiver exceeds a predetermined value.

19. In a carbonated beverage vendor of the type including a refrigeration compartment, improvements comprising: a pre-cooling beverage storage container, means connecting said container with a source of beverage under pressure; a cooling receptacle including a heat-transfer medium; means for refrigerating said medium, said medium and receptacle being exposed to said refrigeration compartment for heat-transfer relative to the latter; a measuring and de-foaming chamber in said medium; a length of conduit in said medium and connecting said storage container and chamber through a first normally closed valve and having a capacity to hold a given volume of beverage for pre-cooling purposes prior to entry into said chamber; a dispensing valve for said chamber and normally closed; a vent valve for said chamber and normally closed; control means for opening said dispensing and vent valves together, and for opening said first valve at a time when said dispensing and vent valves are closed, and auxiliary valve means actuated cooperatively with said dispensing valve when the latter is open for effecting escape of gas at a predetermined controlled rate from said storage container; together with means for automatically regulating the flow of beverage from said source into said storage container dependent upon pressure changes in the latter effected by operation of said auxiliary valve means.

RALPH A. NICHOLSON.
